UNITED STATES PATENT OFFICE.

JOHN LAWSON, OF CENTRAL FALLS, RHODE ISLAND.

CIRCULAR-KNITTING MACHINE.

1,192,329.

Specification of Letters Patent. Patented July 25, 1916.

Application filed June 14, 1912. Serial No. 703,628.

To all whom it may concern:

Be it known that I, JOHN LAWSON, a citizen of the United States, residing at Central Falls, in the county of Providence and State of Rhode Island, have invented 5 certain new and useful Improvements in Circular-Knitting Machines, of which the following is a specification.

This invention relates to what may be 10 termed full automatic circular knitting-machines for producing seamless stockings; an automatic knitting-machine of this general type or class is shown and described in J. D. Hemphill's U. S. Patent No. 933,443 of September 7, 1909.

The object of the invention herewith is to provide knitting-machines, say of the class referred to above, with improved means adapted more especially for the automatic 20 production of hosiery in which the tubular portions thereof, *i. e.*, the leg and foot, are knitted from two or more independent main threads by the coaction of a plurality of 25 series of needles, a pair of cam-blocks, which may be termed main and secondary, respectively, carrying "raise" and "draw" cams and other devices used in connection therewith; the result being to produce in said tubular parts of the stocking wales of interconnected 30 "accordion" stitches. In the formation and production of this type of knitted stitch (accordion stitch) I employ groups of long, medium and short-butt needles (hereinafter designated simply long, medium, and short needles, respectively) arranged in the needle-cylinder as follows:— All the grooves in one-half its circumference carry long and short needles alternating with one another, while all the 35 grooves of the other semi-circumference carry medium and short needles, also alternating. In normal quick-speed tubular knitting during the production of accordion 40 stitches, both the main and secondary cam-blocks are positioned inward contiguous to the cylinder. In this condition all the needles successively engage the raise-cam of the 45 main cam-block and are deflected upward to cast the loops from the latches, as usual, followed immediately by the action of the 50 draw-cam, which in turn successively deflects the needles downward, thereby closing the latches to retain the newly fed main thread in the needle's hooks and at the same 55 time cast off the old loops into the web in a well-known way. When the needles arrive

at the secondary cam-block to receive the corresponding thread, all of them (except the short needles) are actuated substantially as just stated with respect to the main thread and its cam-block. At the same instant, all the short needles, being one-half the total number of needles in the cylinder, are, by means of an intermediate cam, successively diverted downward, below the secondary 65 draw-cam, thereby preventing the short needles from receiving the secondary thread. From this point onward all the needles are carried around by the cylinder to be acted upon by the main raise-cam, as before described, thus producing a web having alternate wales of plain and accordion stitches. 70

In order to produce heel and toe portions in the type of stocking under consideration, the needles in one-half of the cylinder (being 75 all the long needles and the short or jack needles alternating with them) are moved upward temporarily out of knitting action; at the same time the cylinder is rotated in a reciprocatory manner at a reduced rate of 80 speed. The then active needles (being the medium needles and the short needles alternating with them), in connection with the cams of the main cam-block and narrowing and widening picks, are employed to 85 knit the heel-thread into corresponding courses of stitches. The inactive short needles each have a jack mounted therebelow in the corresponding needle-groove. In my improved knitting-machine the act of moving 90 the clutch or analogous member to interlock with the slow-speed member changes the movement of the needle-cylinder from a continuous rotary to a slower, but rotary-reciprocatory movement; the act also simultaneously positions the instep-cam to elevate the 95 long needles, and at the same time automatically positions a jack-cam inward in the path of the butts of the jacks so as to be engaged by the latter for elevating the corresponding short needles out of action. At the same time, too, the secondary cam-block is retracted to the outward position, thereby permitting the active needles to move freely and idly past its face. Concurrently with 100 the secondary cam-block's said outward movement, the corresponding sinker-cam is moved inward, the secondary thread is temporarily withdrawn from knitting action and the widening picks positioned to engage the 105 then active needles. At the completion of the heel part the said temporarily idle de-

5 vices automatically resume their normal functions, that is, the movement of the shipper or clutch to interlock with the quick-speed clutch member causes the cylinder to again move in a continuous rotary manner, the secondary cam-block is moved inward, the jack-cam is moved outward, the instep-cam is moved downward, the upper member thereof at the same time deflecting all the 10 idle needles back into the working plane for normal action, the main threads reintroduced to the needles, and the sinker-cam moved outward again, thus repositioning the devices to produce a tubular web having its 15 circular courses provided with accordion stitches.

In the accompanying six sheets of drawings illustrating an automatic circular knitting machine embodying my invention, and 20 as arranged for producing a tubular knitted web having accordion stitches, Figure 1 is a front side elevation showing the several devices in the normal circular knitting condition. Fig. 2 is a corresponding end elevation, viewed from the left of Fig. 1, some of the parts being omitted. Fig. 3 is a top plan view, in enlarged scale. Fig. 4 is a top plan view of the needle-cylinder, in partial section, showing the arrangement of the groups 25 of needles. Fig. 5 is a transverse sectional view taken on line 5—5 of Fig. 6, showing the jack-cam, etc. Fig. 6 is a partial horizontal sectional view, taken on line 6—6 of Fig. 5. Fig. 7 is an enlarged top plan view 30 of the device for holding the secondary thread in the floating or inactive position. Fig. 8 is a side elevation of the holder. Fig. 9 is an elevation of the main cam-block and its knitting-cams, showing its inner end. Fig. 10 is a similar view of the secondary 35 cam-block and its knitting-cams. Fig. 11 is a cross-section, enlarged, taken on line 11 of Fig. 1, showing arrangement of cam for actuating the secondary cam-block. Fig. 12 is an enlarged end view of the cam for positioning the widening picks. Fig. 13 is a 40 similar view of the cam for actuating the secondary thread-guide and corresponding sinker-cam. Fig. 14 is an end view of the 45 cam for controlling the movements of thread-severing means. The several cams are represented in the relative angular positions. Fig. 15 is a partial transverse sectional view, taken substantially on line α of Fig. 3, showing the secondary thread in the 50 normal and inactive position, and Fig. 16 represents, enlarged, a back view of a portion of the fabric produced.

60 The following is a more detailed description of the improved mechanism, &c., forming the subject of this application for patent, as combined or associated with coöperating elements of an automatic circular knitting-machine. The machine as a whole is capable of producing seamless stockings

having the tubular parts thereof knitted from a plurality of independently introduced main threads (two are shown) which are converted into knitted courses, each course consisting of alternate plain and accordion stitches, which constitute corresponding longitudinal wales in the web or tubular portion. 70

The machine is or may be provided with any suitable driving and speed-changing mechanism. The drawings represent the driving-shaft provided with a sliding clutch b , a clutch-shipper c , pattern-chain C , main cam-shaft s , barrel-cam B secured to the latter, and other coöperating devices to which I 75 make no claim herewith. The shaft s and the members secured thereto make one complete revolution while producing a stocking, or knitted unit, and in one direction only. See arrows. 80

A, in the drawings, designates a frame or housing of a knitting-machine, having the various instrumentalities or elements mounted thereon, constructed and arranged to produce stockings having the characteristic 85 stitch above referred to. The knitting-machine, in general, is substantially like the said patented machine No. 933,443. The table α at the top of the frame supports the revolvable needle-cylinder N and coöperating 90 stitch-forming means. The needle-grooves are elongated to receive vertically movable jacks h . 95

It may be stated here that the drawings show (Fig. 4) three groups of needles in 100 the cylinder, each groove carrying a needle. One-half 2 of the cylinder's circumference is provided with long and short (butt) needles v , v^1 , respectively, alternating with one another. The said jacks h (Fig. 5) are 105 positioned below the short needles v^1 of this half only. The other half 3 of the cylinder carries medium and short (butt) needles v^2 , v^1 only, these also alternating with one another. At two substantially diametrically 110 opposite points movable guides u , u^1 are positioned for the main and secondary threads t and t^1 , respectively; these guides, when in normal use, introduce the threads into the 115 hooks of the needles. See Figs. 1, 2, and 3. 120

At or near the base of the needle-cylinder are mounted diametrically opposed main and secondary cam-blocks D , D^1 , respectively; the said blocks are positioned below the thread-guides which carry the main and secondary threads, respectively. The inner face of the main block D (Fig. 9) is provided with "raise" and "draw" cams x , x^1 , or knitting-cams, and also right and left spring-pressed narrowing-picks P , these latter being brought into action in knitting the heel and toe parts of the stocking, while the cylinder is moving in a rotary-reciprocatory manner, substantially as usual. The other, or opposite, cam-block D^1 is automatically 125

movable in a radial direction; it is also provided with raise and draw cams x^2 , x^3 , respectively, and an intermediate guide-cam x^4 . The inner face of the raise-cam x^2 is provided with a comparatively shallow recess or groove x^5 , the same being located in the path of the butts of the normally traveling needles. As thus devised, the long and medium needles are caused to move upward 10 on the incline x^6 to cast the loops from the latches preparatory to receiving the secondary thread in the open hooks, the cam x^3 meanwhile closing the latches and casting the formed loops from these needles into the 15 web. At the same time the butts of all the other (or alternate) needles, v^1 , v^{11} , freely enter the groove x^5 , without shedding their loops, and are deflected by means of said intermediate guide-cam x^4 downward to 20 join the column of newly threaded needles; all the needles then move upward past the heel of cam x^3 . In Fig. 10 i designates short-butt needles.

In producing the tubular part of the stocking all the needles successively cast the old loops therefrom into the web by means of 25 draw-cam x^1 , at the same time receiving the main thread t into their hooks to form new loops. The column of advancing needles 30 upon arriving at the raise cam x^2 causes the column to separate, as just described.

Fig. 16 represents a developed portion of the circular web, enlarged, viewed from the back or inner face, wherein t indicates the main thread and t^1 the secondary thread; 35 said thread t is fed to the hooks of all the needles in passing the main cam-block D (see Fig. 9), thereby interlocking the main thread with the loops already on the needles and casting said loops therefrom into the web to form the courses 2, 4, 6, etc., indicated in Fig. 16. The circumferential column of needles is automatically divided in passing the secondary cam-block D^1 (Fig. 10), one-half the needles, being every other 40 one, are moved upward to receive the secondary thread t^1 and interlock it with the loops t of these needles at the casting off-point, the other half of the needles, being 45 the intervening or short butt needles, are guided below the secondary thread and do not cast the loops t from the last named needles; the divided column of needles reunite at the base of knitting cam x^3 and move upward to the normal plane to again engage the cam x of block D , in producing 50 the next circular course.

By reason of the fact that all of the needles are caused to knit as they pass the main cams at one course, while only every alternate needle is caused to knit as the needles pass the secondary cams at the next course, the respective wales t^8 and t^9 will be of different formation, as shown in Fig. 16.

In order to change the direction of movement of the cylinder from a continuous rotary (shown in Fig. 1) to a reciprocatory-rotary, so as to knit the heel and toe portions, the intermittent action of the cam B 70 causes the roll c^6 carried on the lower end of the shipper c to pass through a gap b^1 and engage the opposite face of rib c^3 , thereby sliding the clutch to the left to interlock with the reduced speed gearing. At 75 the same time the shipper movement operates, through its link c^1 jointed to the bell-crank lever c^2 , to position the usual lower instep-cam F^1 to temporarily guide all the long needles upward out of action. Simultaneously with this movement a member c^4 (Figs. 5 and 6) connected to said link and operating through a cam-slot c^5 , causes a spring-pressed jack-cam E to move radially inward and position itself in the path of 80 the butts of the said jacks h , thereby causing them to engage the cam E , the result being to move the corresponding short needles v^{11} temporarily upward out of normal action and in horizontal alinement with 85 the idle long needles. It may be repeated here that the jacks are employed only in the cylinder-grooves in which are mounted the short needles v^{11} , alternating with the long needles; therefore these short needles may 90 be termed jack-needles. While these changes are taking place, the secondary cam-block D^1 and its members are moved bodily outward from the cylinder, thereby allowing 95 all the then working needles (being one-half of the total number i . $e.$, the medium needles and the short needles alternating with them) to travel freely past the face of cams x^2 , x^3 , x^4 , while the cylinder is reciprocating. The retraction or outward movement of the cam-block is effected by a cam-lug n of the barrel B , a tilting member n^1 and rod n^2 connected thereto and to a fulcrumed angle lever n^3 , in turn connected to a horizontal link n^4 100 jointed to a supported swinging lever n^5 110 whose opposite end is jointed to a member n^6 carrying rods n^7 fixed to the block D^1 . Springs d^2 automatically reposition the block inward when the front or free end of member n^1 again engages the barrel's 115 surface.

Concurrently with the outward movement of the secondary cam-block D^1 other mechanisms are employed for moving the secondary knitting-thread t^1 and secondary sinker-cam e out of normal position and action, as follows: A cam C^1 , fixed to shaft s , is provided with peripherally separated cam-lugs f ; these latter, when engaged by the free end of a pivotally mounted horizontal lever l , move the connected members l^1 , l^2 in a vertical direction. A guided vertically extending spring-pressed rod l^3 is supported by the pivoted arm or member l^2 ; the upper end of the rod is wedge-shaped and adapted 125 130

to engage with and actuate the secondary sinker-cam e . At the same time an upwardly extending arm u^3 , fixed to rod l^3 , is adapted to actuate the secondary thread-guide u^1 pivoted to a bracket u^2 fixed to the latch-guard H and bodily movable with it. As thus devised, the act of moving the rod l^3 upward also moves the secondary sinker-cam e outward, corresponding with the normal 10 knitting position, and also swings the secondary thread-guide to place its thread in normal knitting action, the secondary knitting-cams then, of course, being in the inward position; a reverse or downward movement of the rod l^3 , in connection with the spring t^4 , operates to withdraw the vertical rod from sinker-cam e , the spring e^1 automatically moving it (cam e) inward to its limit. At the same instant, too, the rod 15 l^3 is withdrawn from the thread-guide u^1 , thereby enabling the spring t^3 to automatically swing the guide through the opening s^1 of the latch-guard, thus carrying its thread inward back of the needles and out 20 of knitting action, or floating; Figs. 7 and 15 represent the position of the idle secondary thread t^1 when the cylinder is moving in a rotary-reciprocatory manner. The engagement of the lever l with the peripheral 25 surface of a lug f places and holds the elements u^1 and e in the normal knitting positions.

Contiguous to the said cam C^1 is secured to the intermittently movable cam-shaft s a cam C^2 , which may be termed the widening-cam. This last-named cam in its angular movements actuates a suitably fulcrumed horizontal lever d having its rear end jointed to a vertical link d^1 , in turn jointed at 30 the top to a pivoted lever d^2 having a vertically guided spring-pressed rod d^4 supported on the lever's free end. The rod d^4 , in connection with means of well-known or usual construction, together with said cam C^2 , are caused to position the widening-picks P^1 as required during the knitting of the heel and toe pockets of a stocking.

While the needle-cylinder is being rotated in a reciprocatory manner and producing 50 the said heel and toe portions the secondary main knitting-thread is held in a temporarily inactive or "floating" condition by means about to be described. A substantially flat horizontal base or plate B^1 is 55 normally located within the needle-row, and is detachably secured to the swinging latch-guard H by screws passing through a bent arm f^1 into a rearward extension of the latch-guard. To the upper face of the member B^1 is adjustably secured a thread-holder device L adapted to hold the secondary thread while it is being oscillated idly or floating to and fro in unison with the reciprocating cylinder and its attached work. The member L (shown most clearly in Figs.

7, 8, and 15) consists of a substantially flat plate r having its inner edge cut to produce a narrow open slit r^1 to receive the secondary thread t^1 and hold it therein when it is floating or reciprocating with the cylinder. 70 The plate part r^2 adjacent the slit is bent to assist in guiding the thread into the opening. The outer edge of the holder forms a well-rounded flange r^3 terminating in an upturned end r^4 . A portion of the stock at a 75 point opposite said slit r^1 is bent upwardly to produce an elongated guide-arm member r^5 adapted to further insure the proper presentation of the secondary thread to the needles during circular knitting. Figs. 7 80 and 15 indicate a position of the thread t^1 when the cylinder is reciprocating, the inner end portion t^6 of the thread when thus floating being still connected to the web. A thread-severing device, indicated at H^1 , and a binder or clamping device, indicated at H^2 , for engagement with a knitting-thread (but not with the secondary thread) are secured to said plate B^1 and are also capable of swinging bodily with the latch-guard. I may state, however, that I make no claim broadly herewith to thread-severing and thread-clamping means. These last-named devices are adapted to be actuated and controlled through the medium of 90 a comparatively long lever k pivoted to the latch-guard, and suitable co-operating members, connected to the lever. The rearwardly extending arm k^1 of the lever is provided with an arcuate slot, in the outer end 100 of which is slidably supported and jointed a guided, downwardly extending connecting rod k^2 , in turn connected to intermediate members which are moved by means of a pivoted lever k^3 whose front or free end k^4 105 normally rests upon the periphery of the cam C^3 . At certain places in the stocking-knitting operation where threads are to be temporarily moved out of knitting action and severed the last-named cam is provided with correspondingly positioned cam-lugs or dogs m which cause the lever k^3 to oscillate quickly and operate cutters whenever the lever engages a lug. Said action, in connection with the lever k , &c., also operates the said thread-clamping device H^2 at 110 the same time.

In the production of stockings upon my improved knitting machine, constructed to employ independent main and secondary knitting-threads, *i.e.*, double-feeding means, simultaneously, the same in knitting the normal tubular portions of the web also produces in said tubular parts circularly arranged parallel longitudinal rows or wales 115 120 125 of different formation, as shown in Fig. 16.

In order to change the movements of the needle-cylinder of my improved circular knitting-machine from continuous rotary to rotary reciprocating movements, as in knit- 130

ting the heel and toe portions of a stocking in which the tubular web parts thereof consist of continuous courses of alternate plain and accordion stitches produced from main 5 and secondary threads, substantially as just described, the secondary thread and its knitting means are moved out of normal knitting action, and all the needles in a semi-circumference of the cylinder also moved upward out of action temporarily at the same time; these idle needles comprise the long 10 butt and jack needles. Simultaneously with said changes the narrowing and widening picks, together with the corresponding 15 threads, are positioned for normal action substantially as usual, followed later by re-positioning the main and secondary threads and coöperating means to resume normal circular knitting in which the courses consist of plain and accordion stitches, as before 20 stated.

I claim:

1. In a circular knitting machine, the combination of a needle-cylinder provided 25 with alternating long and short-butt needles, means for feeding main and secondary threads to the needles, main knitting cams positioned to engage and actuate all said needles to knit with the main thread, a second set of knitting cams comprising a cam constructed to engage and actuate the alternating long-butt needles to knit with the secondary thread and to cause the alternating short-butt needles to pass by said second set of knitting cams without knitting, and pattern-controlled means for moving said last-named cam into and out of needle-engaging position.

2. In a circular knitting-machine, the combination of a needle-cylinder provided 40 with alternating long and short-butt needles, independent means for feeding main and secondary threads to the needles at oppositely disposed points, a main cam-block 45 provided with needle-elevating and needle-depressing cams positioned to be engaged at that point by the butts of all the needles during rotary knitting, a secondary cam-block provided with normal needle-elevating and normal needle-depressing cams, said needle-elevating cam arranged to raise 50 the butts of the long-butt needles only, an auxiliary needle-depressing cam located intermediate the said needle-elevating and 55 needle-depressing cams of the secondary cam block, whereby during the said rotary knitting all the long-butt needles are normally actuated to cast loops from the latches and take in the secondary thread, while at the same time the alternate or short-butt needles pass direct to said auxiliary cam and are deflected by it without casting loops 60 from the latches or taking in the secondary thread, the two classes of needles later reuniting in a single column to be successively

normally acted upon by the knitting-cams of said main cam-block, means for moving radially the secondary cam-block bodily from the needle-cylinder, and means for actuating the latter in a rotary-reciproca- 70

3. In a circular knitting-machine, the combination of a needle-cylinder provided with alternate groups of long and shorter-butt needles, a main cam-block provided 75 with needle-elevating and needle-depressing cams positioned to be normally and operatively engaged by the butts of all the needles, means for feeding a main thread to said needles during rotary knitting, a secondary cam-block provided with normal needle-elevating and normal needle-depressing cams for operative engagement with the long-butt needles, an auxiliary needle depressing cam located intermediate the two 80 said secondary needle actuating cams for moving the short-butt needles only, said auxiliary cam being secured to the secondary cam-block, and means for introducing a secondary thread to the long-butt needles, constructed and arranged whereby during the 85 knitting of rotary courses all the long-butt group of needles in passing the secondary cams are normally actuated to cast their loops and take in the secondary thread, 90 while at the same time the alternate or short-butt group of needles are deflected by means of said auxiliary cam to reject the secondary thread, all the needles of the cylinder later passing in succession to the 95 main cam-block to be acted upon by its cam in knitting the corresponding circular course, substantially as described.

4. The combination, in an automatic circular knitting-machine, of a grooved knitting-cylinder having a circular row of needles mounted therein, oppositely positioned main and supplemental knitting-cams, means for feeding a main knitting-thread to all the needles to be normally and 105 successively acted upon by the main knitting-cams, means for successively feeding a secondary knitting-thread to each alternate needle of said needle row, means for automatically positioning said supplemental 110 knitting-cams with respect to the needle-cylinder so as to be engaged by the said alternate needles and at the same time casting loops from the last named needles in knitting the corresponding circular course of the 115 web being produced, said secondary thread-feeding means including in its construction a mounted swinging lever automatically positioned to feed its thread to the needles concurrently with the act of positioning the 120 said supplemental knitting-cams.

5. The combination, in an automatic circular knitting machine, of a rotary needle-cylinder having groups of long butt, short-butt and short-butt jack-needles mounted 125

therein, independently movable guides for main and secondary knitting-threads, respectively, main and secondary knitting-cams arranged in relation to said guides, 5 speed-changing mechanism, including a movable clutch member, and means controlled by said member for rendering the long-butt and short-butt jack-needles temporarily inoperative upon moving the said clutch-member from mechanism causing continuous 10 rotary action into mechanism adapted to move the cylinder in a rotary-reciprocatory manner.

6. The combination, in an automatic circular knitting machine, of a revoluble cylinder having groups of long-butt, short-butt, and short-butt jack-needles mounted therein, main and secondary knitting-cams, speed-changing mechanism, including a movable 15 clutch element, an instep-cam, a jack-cam, and means connected with said clutch-element and said instep and jack cams, whereby the act of moving the clutch to actuate the cylinder in a rotary-reciprocatory manner simultaneously positions the jack-cams and causes them, in coaction with the instep cams, to move the long-butt and short-butt jack-needles upward out of knitting action.

7. The combination, in an automatic circular knitting-machine, of a revoluble cylinder having groups of long-butt, short-butt, and short-butt jack-needles mounted therein, main and secondary knitting-cams, means for feeding main and secondary knitting 30 threads to the needles, an instep-cam, a jack-cam, speed-changing mechanism, including a clutch element, and means cooperating with the latter and with said instep and jack cams and with said secondary thread-feeding means and secondary knitting-cams, whereby upon moving the clutch in one direction the said long-butt and short-butt jack-needles and the said secondary thread-feeding and secondary knitting-cams are 35 moved out of knitting action simultaneously, for the purpose set forth.

8. In a rotary cylinder knitting-machine having groups of suitably disposed long-butt, short-butt and short-butt jack needles, mov- 40 ably mounted therein, and speed-changing means, including a slideable clutch element, the combination therewith of a radially movable jack-cam, jacks mounted below said short-butt jack-needles and engageable with them,

a vertically movable instep-cam, and means 55 for positioning said instep and jack cams, whereby the co-action of the revolving cylinder and jacks causes the corresponding short-butt jack and long-butt needles to move upward out of knitting action simulta- 60 neously.

9. In an automatic knitting-machine having a revoluble knitting-cylinder provided with sets of needles having butts varying in length, the combination therewith of a vertically movable instep-cam, a radially movable jack-cam positioned below the instep-cam, jacks mounted below and engageable with certain of the needles, and means in continuous engagement with speed-changing 70 mechanism for positioning the said jack and instep-cams in the respective circular paths of the corresponding needles to cause them to be temporarily moved upward out of knitting action.

75

10. In a double-feed hosiery knitting-machine provided with a needle-cylinder having two groups of needles movably mounted therein, in which the needles of one group alternate (singly) with the needles of the other group, and means for actuating the needle-cylinder, the combination therewith of a main cam-block having raise and draw cams secured thereto for causing all the needles to knit in succession, a secondary cam-block, independent raise and draw cams secured to its inner face, said raise cam arranged to elevate only the needles of one group, an auxiliary cam disposed between the last-named raise and draw cams and 85 also secured to the secondary cam-block, said auxiliary-cam arranged to be engaged by the needles unacted upon by the said secondary raise cam and deflect them downward below the secondary thread feeding point, 90 the two groups of needles being reunited in passing under the secondary draw cam, a cam path arranged to guide the said reunited column of needles upward to a common plane, and means for moving the sec- 100 ondary cam-block radially relatively to the needle-cylinder.

In testimony whereof I have affixed my signature in presence of two witnesses.

JOHN LAWSON.
